UNITED STATES PATENT OFFICE.

GEORGE G. FLOYD, OF CHICAGO, ILLINOIS, ASSIGNOR TO AMERICAN STEEL FOUNDRIES, OF CHICAGO, ILLINOIS, A CORPORATION OF NEW JERSEY.

JOURNAL-BOX-RETAINING DEVICE.

Application filed October 30, 1924. Serial No. 746,908.

This invention relates to a journal box retaining device.

One object of the invention is to provide a simple, durable and efficient retaining device for journal boxes, whereby journal boxes are prevented from accidental displacement with respect to the pedestal jaws of the side frame.

Another object is to provide a journal box retaining device adapted to meet the various requirements under service conditions.

These and other objects are accomplished by means of the arrangement shown on the accompanying sheet of drawings in which,

15 Figure 1 is a fragmentary side elevation of a railway car truck side frame showing pedestal jaws, a journal box and retaining means for the latter embodying my invention; and,

20 Figure 2 is a fragmentary top plan view of the same.

The various novel features of the invention will be apparent from the following description and drawings and will be particularly pointed out in the appended claims.

Referring to the figures on the drawings, it will be noted that my invention is illustrated in connection with a railway car truck side frame 10, having an outer pedestal jaw 11 and an inner pedestal jaw 12, between which a journal box 13 is received. The journal box jaws 11 and 12 have the usual guide surfaces 14 and 15 respectively, which are adapted to cooperate with the corresponding vertical walls 16 and 17 respectively of the journal box 13. The journal box is provided with the usual side flanges or ribs 18, which embrace lateral sides of the pedestal jaws 11 and 12 for limiting relative lateral movement between said jaws and journal box.

This invention has to do primarily with means for retaining the journal box against accidental vertical displacement with respect to the side frame,—for example, in the case of derailments. In this connection it will be noted that the inner journal box jaw 12 is provided with a downwardly extending projection 19, having a transversely arranged lock receiving groove 20 therein, said groove extending the entire distance across the jaw. It will be noted that the inside face 21 of the projection 19 is not a guide face for the journal box in any manner whatsoever, and

as a matter of fact is offset with respect to the associated vertical guide face 15 of the pedestal jaw 12. The sole function of the projection 19 is to provide a support in which the lock receiving groove 20 may be formed without in any way affecting the guide face 15 of the jaw. One leg 22 of an L shaped lock member 23 is removably mounted in said groove 20 and is vertically aligned with and underlies two of the ribs or flanges 18 on one side of the journal box for the purpose of preventing the journal box from being displaced in a vertical direction with respect to the pedestal jaws. The other leg 24 of the L shaped lock member 23 extends alongside of the outer side face of the pedestal jaw 12 and has an eye portion 25 for the reception of a retaining bolt 26. This bolt passes through an opening 27 in the pedestal jaw 12 and has its head 28 on the interior side of the flange 29 of the pedestal jaw 12. After said retaining bolt 26 is passed through the opening 27 and through the eye portion 25 of the lock member, the nut 30 is applied to the threaded end of the bolt 26 for retaining the lock member 23 in its normal locking position. A cotter pin or a similar member 31 is passed through an opening in the bolt 26 for preventing the nut 30 from being accidentally removed from the bolt.

By means of this arrangement, not only is the journal box prevented from lateral displacement with respect to the journal box jaws, but also the journal box is prevented from accidental vertical displacement with respect thereto.

I claim:

1. In a railway car truck, the combination of a side frame having inner and outer pedestal jaws, the inner pedestal jaw having a projection with a lock receiving groove therein extending transversely of said side frame, a journal box mounted in said jaws and having means for cooperating with the jaws to limit relative lateral movement therebetween, and a lock member extending transversely of said side frame mounted in said groove and adapted to engage a portion of said journal box to prevent accidental vertical displacement of said journal box with respect to said jaws.

2. In a railway car truck, the combination of a side frame having pedestal jaws, one of which jaws being provided with a projec-

tion having a lock receiving groove therein along one side, a journal box mounted in said jaws and cooperating therewith whereby relative lateral movement therebetween is limited, and a lock member extending transversely of said side frame mounted in said groove and cooperating with a portion of said journal box to prevent accidental vertical displacement of said journal box with respect to said jaws.

3. In a railway car truck, the combination of a side frame having pedestal jaws, one of which jaws being provided with a projection having a laterally extending lock receiving groove therein, a journal box mounted in said jaws and having means to cooperate with said jaws to limit relative lateral movement with respect thereto, and an L shaped lock member, one portion of which is mount-

ed in said groove for engaging a portion of 20 said journal box to prevent accidental vertical displacement of said journal box with respect to said jaws, and another portion of said lock being secured to the associated jaw.

4. In a railway car truck, the combination 25 of a side frame having pedestal jaws, one of which jaws has a projection offset inwardly with respect to the vertical guide face of said jaw and has a lock receiving groove thereon, a journal box mounted between said jaws, and a lock member mounted in said groove for engagement with a portion of 30 said journal box to prevent displacement of the latter with respect to said jaws.

Signed at Chicago, Illinois, this 27th day 35 of October, 1924.

GEORGE G. FLOYD.
